Design U.S. Appl. No. 29/420,446, filed May 9, 2012, In re: Fuchs;
entitled *Eyeglasses*.

(Continued)

Primary Examiner — Raphael Barkai(74) *Attorney, Agent, or Firm* — Alston & Bird LLP(57) **CLAIM**I claim the ornamental design for eyeglasses, as shown and
described.

DESCRIPTION

FIG. 1 is a perspective view of eyeglasses showing my new
design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof, the right side being
a mirror image thereof; and,FIG. 7 is a side elevation cross-section view thereof taken
along line 7-7 in FIG. 4.The broken lines are directed to environment or unclaimed
features. The broken lines form no part of the claimed design.**1 Claim, 5 Drawing Sheets**(56)
